UNITED STATES PATENT OFFICE

161,142

VAPORIZER

Carl W. Sundberg, Birmingham, Mich., assignor to The De Vilbiss Company, Toledo, Ohio, a corporation of Ohio

Application February 3, 1950, Serial No. 7,684

Term of patent 14 years

(Cl. D83—1)

To all whom it may concern:

Be it known that I, Carl W. Sundberg, a citizen of the United States, residing at 1260 Lynhurst Road, Birmingham, in the county of Oakland and State of Michigan, have invented a new, original, and ornamental Design for a Vaporizer, of which the following is a specification, reference being had to the accompanying drawing, forming part thereof.

In the drawing:

Fig. 1 is a side elevational view of a vaporizer, showing my new design; and

Fig. 2 is a top plan view thereof.

The side opposite that shown in Figure 1 is similar thereto.

I claim:

The ornamental design for a vaporizer, as shown and described.

CARL W. SUNDBERG.
